United States Patent Office.

ISAAC N. BUCK, OF ELGIN, ILLINOIS.

Letters Patent No. 85,066, dated December 22, 1868.

IMPROVEMENT IN BURGLAR-ALARM.

The Schedule referred to in these Letters Patent and making part of the same.

To whom it may concern:

Be it known that I, ISAAC N. BUCK, of the city of Elgin, county of Kane, State of Illinois, have invented a certain new and improved Burglar-Alarm; and I do hereby declare the following to be a clear and exact description thereof, reference being had to the accompanying drawings.

Figure 1 represents the interior of a case containing one of my alarms.

A represents the case or shell.

B represents the striking-apparatus, similar to that in most clocks, and containing nothing novel in its nature.

C, the bell for giving alarm.

D, the vibrating rod, which controls the action of the striking-mechanism.

D D, a stud, against which the rod D rests, and by which it is held in position when no alarm is desired.

E represents a sliding bolt, one end of which projects through the case, as that of any common lock.

F represents a key-bolt, placed perpendicularly in the case; the upper end of which, by contact with the shoulder shown on sliding bolt E, prevents its advancing beyond the case, from pressure of the spring next described.

H represents a wire spring, attached to a stud, as shown at H H, being at its upper end in contact with pressure against the pin or stud in sliding bolt E, as shown at point E E, and at its lower end against pin F F. Its office is to not only steady the key-bolt F, but to cause such pressure as will throw the sliding bolt forward, if released by the downward movement of the key-bolt, caused by turning the key, when inserted at G.

This figure represents my alarm before being set for operation.

The mode of applying the apparatus is by insertion into the door-casing or jamb, so that the sliding bolt E would come in contact with the back edge of the door when closed.

During the day, the key-bolt F being raised to po-

sition as shown in fig. 1, the door could be opened and closed without giving an alarm.

At night, or such time as an alarm would be required, the door is closed, the key-bolt F drawn down by the interposition of the key at G, permitting the sliding bolt E to rest, with its pressure from spring H, against the edge of the door.

Should the door be opened, it is obvious that the sliding bolt E would advance, following the movement of the door, thus releasing the vibrating rod at D D, causing the pallet-escapement wheel and hammer to operate, sounding the bell rapidly and loudly, giving the alarm.

Figure 2 represents, as in fig. 1, similar parts, lettered alike, and differs from that, in having the key-bolt drawn down, the sliding bolt advanced; and the alarm free to operate.

It is plainly seen that my alarm can as well be applied to the threshold, side, or top of a door-frame or door, to the sill of a window-frame or its side, and work the same result as that which has already been described.

I am aware that many burglar-alarms have been invented and used, in which clock-work constituted the striking-mechanism, in connection with a bell.

I therefore claim as my own invention, and desire to secure by Letters Patent—

1. The sliding bolt E, with its studs E E and D D, arranged and operating in connection with the vibrating or pallet-rod D, substantially as described.

2. The key-bolt F; arranged and operating substantially as described.

3. The key-bolt F, spring H, sliding bolt E, and the striking-mechanism, arranged substantially as described, for the purposes specified.

ISAAC N. BUCK.
